UNITED STATES PATENT OFFICE

CLEMENT PIERCE WILSON, OF CEDAR RAPIDS, IOWA

CLINCHING PRESS

Application filed May 31, 1929. Serial No. 367,496.

This invention relates to foot-presses used for forming and clinching wire products, and the like, the object of the invention being to produce a press adapted to clinch the tangs 5 of a staple around a welt at the edge of tent curtains to form projecting eyes for lacing and stretching, instead of the grommets commonly employed for that purpose.

The invention is fully disclosed in the description and claims following, reference being had to the accompanying drawing, in which:—

Fig. 1 is a side elevation of a press embodying the invention. Fig. 2 is a front elevation 15 of the upper part of the press. Fig. 3 is a vertical section of the same, on the line 3—3 of Fig. 2. Fig. 4 is a fragmentary view opposite that of Fig. 1, showing details of the upper portion of the press. Fig. 5 is a view 20 in perspective of a staple to be clinched by the press. Fig. 6 shows in perspective the staple clinched about a marginal welt.

In the drawing, the numeral 5 denotes the press-head, which is mounted on a suitable 25 column 6, of tubular material, and that on a base 7 carrying a foot-lever 8. The foot-lever connects by a rod 9 with a plunger lever 10 pivoted at 11. A plunger 12 is mounted slidably in a guideway formed in the press-head, 30 and connects with the lever 10 by links 13. A spring not shown serves to carry the foot-lever end connected parts to the elevated position, according to familiar press construction.

35 At the lower end of the plunger is formed a semi-cylindrical groove 14, which, when the plunger is depressed, matches a corresponding groove 15 in a die 16 set on a forwardly extending shoulder of the press-head. 40 The die also is provided with a gauge-plate 17 to serve as a back-stop for the loop of the staple when set for clinching. Forward of this back-stop is a pair of upstanding pins 18 to serve as a similar stop for the fabric 45 and welt, as shown in Fig. 4.

In front of the plunger is mounted a presser-plate 19 by its slotted side flanges 20 engaging studs 21 set in the press-head. The presser-plate connects with the plunger lever 50 by links 22. A tension coil spring 23 connects

at one end with a stud 24 on the presser-plate, and at the other end by another stud 25 to the head. The tension of the spring tends to hold the presser-plate to normal position against the front of the press-head. The side slots permit it to slide vertically a limited distance when forced downwardly by the plunger lever, and concurrently with the latter. The lower end of the presser-plate is formed as a rather broad finger 26, extending inwardly, and slotted at 27 to admit the tangs of the staple 28. In the preliminary act of attaching the staple to the fabric the presser-plate forces the fabric down over the staple tangs preparatory to the final clinching of the tangs. During this part of the operation the presser-plate is controlled by a grooved guide 29 attached to the press-head, the groove in the guide being engaged by a rib 30 formed on the presser-plate. When, however, the presser-plate has reached the limit of its downward movement, as limited by the slots and studs 21, it is disengaged from its guide, and is then forced to swing outwardly by the further movement of the plunger and its lever. This frees the presser-plate from the tangs of the staple, and allows the plunger, which has followed its downward movement, to clinch the tangs. These, under the final pressure of the plunger, 30 take the form shown in Fig. 6, tightly encircling the welt 31 formed by enclosing a cord 32 in a fold of the fabric 33.

The extending loop of the staple makes a very convenient eye for the attachment of a tent-rope, or the like, and a heavy strain on the rope does not tend to tear the fabric as does a like strain on a grommet.

It is to be noted further that the operation is simple and rapid, no preliminary punching of the fabric being required, as in the application of eyelets or grommets.

Having thus described my invention, I claim:

1. A press of the designated character having a die to support the loop of a staple having upturned tangs, a cooperating plunger to form the tangs as eyes about a welted fabric, means for forcing the plunger to clinching position, a pilot presser-plate adapted to force 100

the fabric down over said tangs, and means whereby the presser-plate is shifted from under the plunger to permit the final clinching of the tangs around the welt.

5 2. A press of the designated character, having a die to support the loop of a staple having angled and upturned tangs, a cooperating plunger to form the tangs as eyes around a welted fabric, means for forcing the plunger to clinching position, a pilot presser-plate having a slotted finger to receive the upturned tangs and force the fabric thereover, a guide for the presser-plate during the puncturing of the fabric, and means adapted to shift the 10 finger of the presser-plate out of the path of the following plunger.

15 3. In a press of the designated character, a die adapted to guide and support the loop of a staple having angled and upturned tangs, 20 and having a guide-stop for a welted fabric, a plunger cooperating with the die to clinch said tangs around the welt, a tiltable and slidable presser-plate having a slotted finger preceding the plunger and adapted to force 25 the fabric over the tangs, a guide for the presser-plate during its said operation, means cooperating with both the plunger and presser-plate to actuate them in their working movements, and to tilt the presser-plate 30 outwardly from under the plunger, and a recoil spring adapted to restore the presser-plate guide-engaging position.

35 4. In a press of the designated character, a die to support the body of a staple having upturned tangs, a plunger cooperating with the die to clinch the tangs about a welted fabric, a lever to actuate the plunger, a presser-plate having a slotted finger to admit the tangs and disposed ahead of the plunger, 40 a guide for the presser plate while forcing the welted fabric over the tangs, a diagonally disposed link connecting the presser-plate with the plunger lever, and adapted to tilt it outwardly to clear the plunger when released from the guide, and a spring in operative connection with the presser-plate to restore it to normal position.

In testimony whereof I affix my signature.
CLEMENT PIERCE WILSON.
